UNITED STATES PATENT OFFICE

DAVIS MARINSKY, OF NEW YORK, N. Y.

SEPARABLE FASTENER

Application filed April 25, 1931. Serial No. 532,747.

This invention relates to separable fasteners consisting of two stringers having inter-engaging coupling elements, and a slider movable along said stringers in coupling and uncoupling the same; and the object of the invention is to provide stringers of the class specified, wherein independent coupling elements are secured to one edge portion of a strong or comparatively heavy mounting 10 tape with the coupling portions of said elements projecting beyond the edge of the tape, and wherein a supplemental strip of relatively thin material is provided with a series of apertures or openings centrally 15 thereof, through which the projecting ends of the coupling elements are adapted to pass; the side edges of said strip being disposed above and below the first named strip; a further object being to provide a supplemental strip for stringers of the class specified, wherein said strip may be composed of different colors and of a texture suitable for and consistent with the article in connection with 20 which the stringers are mounted, said supplemental strip being constructed of cotton, silk, fibre silk or any other suitable material; a further object being to provide a supplemental strip of the class specified, which in addition to enhancing the appearance of the 25 device, also serves to cover that part of the coupling elements arranged upon and attached to the first named strip; and with these and other objects in view, the invention consists in a device of the class and for the 30 purpose specified, which is simple in construction, efficient in use, and which is constructed as hereinafter described and claimed.

The invention is fully disclosed in the following specification, of which the accompanying drawings form a part, in which the separate parts of my improvement are designated by suitable reference characters in each of the views, and in which:—

Fig. 1 is a diagrammatic, detail view of a 45 part of a fastener made according to my invention, with parts of the construction broken away; and,

Fig. 2 is a transverse, sectional view of the 50 structure shown in Fig. 1 on an enlarged scale, showing one of the stringers in full

lines and indicating the other in dotted lines.

In the drawings, I have shown for the purpose of illustrating one use of my invention and one method of carrying the same into effect, two stringers 10 and 11 and a slide 55 member 12 having a finger piece 13 movable along said stringers in coupling and uncoupling the same. The structure of each stringer is identical, so that the brief description of one will apply to the other. 60

Each stringer consists of a mounting strip 14 of strong, durable material, to one edge of which is secured a plurality of coupling elements 15, which in the construction shown are similar to the coupling elements shown 65 and described in a prior patent granted to me September 9, 1930, Number 1,775,353.

The elements 15 are formed from short pieces of wire fashioned centrally to form coupling loops 16 having offset outer ends 17. 70 One end portion 18 of the wire extending from each loop 16, is arranged upon one side of the strip, and the other end portion 19 on the other side face of said strip, the inner ends of said end portions piercing the strip 14 75 at spaced intervals as indicated at 20 and folded upon opposite side faces of the strip in securing the separate coupling elements 15 to said strip, it being understood that the end portions 18 and folded ends are compressed 80 onto the strip to retain them against movement relatively thereto.

After the strip 14 with a predetermined number of coupling elements 15 arranged thereon is formed, a supplemental strip 21 is 85 mounted in connection with the first named strip and coupling elements by passing the central apertured portion 22 of the strip over the coupling elements 15 to extend the side 90 portions 23 and 24 of the strip 21 upon opposite side faces of the strip 14, it being understood that the side portions 23 and 24 cover the end portions 18 and 19 of the separate coupling elements. The side portions 23 95 and 24 are secured together and to the strip 14 by a line of stitching 25, leaving the end portions of the strips 14 and 21 free for mounting in connection with a suitable support which may be arranged upon all of said strips or between the strip 14 and either end 100

portion 23 and 24 of the strip 21, as desired. The strip 21 may be composed of any suitable material, which need not be of the strength of the material employed in the strip 14, and may in fact, consist of a relatively light strip of cotton, silk, fibre silk, leather, imitation leather, or may consist of a sheet of rubber or a rubberized sheet, depending entirely upon the nature of the article in connection with which the stringers are to be mounted.

One of the advantages of my improved structure resides in the fact that the stringers involving the strip 14 with the coupling members or links thereon may be manufactured with a common type, form and color of strip 14, thus standardizing the construction of this part of the complete device. The supplemental strip 21 which is applied to the standardized stringer will be of such color, texture and structure as to suit the particular article or product in connection with which the stringers are to be mounted. This strip may be of any desired width and is preferably 25 of greater width than the width of the strip 14.

It will also be apparent that in the use of rubber or pressed sheets, or in fact in the use of a sheet of any desired texture, the stitching operation as at 25 is not absolutely necessary, as the separate sheets may be secured together by vulcanization or by the use of a suitable cement or adhesive.

In addition to facilitating the merchandising of stringers of the class under consideration, the use of the supplemental strip also serves to cover portions of the coupling members on the strip 14, and also reinforces and strengthens the complete stringer. It will be understood that while I have shown for the purpose of illustrating one use of my invention, a particular type of coupling member, my invention is not necessarily limited in this respect, nor am I limited to the specific structure of the strips herein shown and described, and various changes therein and modifications thereof may be made within the scope of the appended claims without departing from the spirit of my invention or sacrificing its advantages.

Having fully described my invention, what I claim as new and desire to secure by Letters Patent is:

1. A separable fastener of the class described involving stringers having interengaging coupling elements, each stringer consisting of an elongated mounting strip, coupling elements attached to one edge only of the strip and projecting beyond said edge, and a supplemental strip of thin fibrous material having longitudinally spaced openings arranged centrally thereof adapted to be passed over the projecting ends of said coupling elements to dispose the side portions

of the supplemental strip above and below the first named strip.

2. A separable fastener of the class described involving stringers having interengaging coupling elements, each stringer consisting of an elongated relatively flat thin mounting strip, coupling elements attached to one edge of the strip and projecting beyond said edge, a supplemental strip of thin fibrous material having longitudinally spaced openings arranged centrally thereof adapted to pass over the projecting ends of said coupling elements to dispose the side portions of the supplemental strip above and below the first named strip, and said supplemental strip being of a texture contrasting to that of the first named strip.

3. A separable fastener of the class described involving stringers having interengaging coupling elements, each stringer consisting of an elongated mounting strip, coupling elements attached to one edge only of the strip and projecting beyond said edge, a supplemental strip of thin fibrous material having longitudinally spaced openings arranged centrally thereof adapted to pass over the projecting ends of said coupling elements to dispose the side portions of the supplemental strip above and below the first named strip, said supplemental strip being of a texture contrasting to that of the first named strip, and means adjacent the coupling elements for securing the supplemental strip to the first named strip.

4. A separable fastener of the class described involving stringers having interengaging coupling elements, each stringer consisting of an elongated mounting strip, coupling elements attached to one edge only of the strip and projecting beyond said edge, a supplemental strip of thin fibrous material having longitudinally spaced openings arranged intermediate the edges thereof and adapted to be passed over the protruding ends of said coupling elements to dispose the side portion of the supplemental strip above and below the first named strip, and the side portions of said second named strip being arranged over that portion only of the coupling elements arranged on the first named strip.

5. A stringer for fastening devices of the class described comprising a strong mounting tape, a plurality of coupling elements attached to one edge of the tape and having portions disposed on upper and lower surfaces thereof and with coupling parts projecting beyond said edge, the other edge of the tape being free for attachment to a suitable support, and a supplemental facing strip of thin material fashioned to pass over the projecting coupling parts of said coupling elements to arrange side portions of the supplemental strip above and below the tape.

6. A stringer for fastening devices of the

- class described comprising a strong mounting tape, a plurality of coupling elements attached to one edge of the tape and having portions disposed on upper and lower surfaces thereof and with coupling parts projecting beyond said edge, the other edge of the tape being free for attachment to a suitable support, a supplemental facing strip of thin material fashioned to pass over the projecting coupling parts of said coupling elements to arrange side portions of the supplemental strip above and below the tape, and means for securing the supplemental strip to the tape.
- 15 7. A stringer for fastening devices of the class described comprising a strong fabric tape, a plurality of coupling elements attached to one edge only of said tape and spaced longitudinally thereof, with parts of said elements disposed on opposite faces of said tape, the coupling parts of said elements projecting outwardly beyond said edge, and a finishing and mounting strip thinner than said tape and attached thereto, said strip being arranged inwardly of the coupling parts of said elements and covering the parts of said elements on the tape and the major part of the tape.

20 In testimony that I claim the foregoing as my invention I have signed my name this 24th day of April, 1931.

DAVIS MARINSKY.
